COMBINED CIRCUIT AND FLASHLIGHT
BATTERY CONNECTION

Douglas Ralph Clarke, Toronto, Ontario, Canada

Application July 17, 1936, Serial No. 91,176

6 Claims. (Cl. 240—10.61)

My invention relates to improvements in combined circuit and flashlight battery connections, and the object of the invention is to devise a connection for a battery which will serve both for the ignition circuit and a flashlight, in which the flashlight is operable independently of the ignition circuit when connected or disconnected from the battery so that the flashlight may be used either as a signal light when the battery is also operating the ignition circuit or as a portable light when the ignition circuit is disconnected, and it consists essentially of the arrangement and construction of parts all as hereinafter more particularly explained.

15 Fig. 1 is a perspective view of a battery showing my flashlight and ignition circuit connector applied thereto.

Fig. 2 is a sectional view through the connector and the adjacent portion of the battery and its terminal.

20 Fig. 3 is a rear end elevation of the connector applied to the adjacent portion of a battery, such portion being shown in section.

Fig. 4 is a perspective detail of the two members separated apart forming the connection between the ignition circuit and the ungrounded terminal of the battery.

25 In the drawing like letters of reference indicate corresponding parts in the different views.

30 1 indicates a battery of any suitable type provided with a metal casing and with a handle 2 by which it is rendered portable and the positive and negative terminals 3 and 4 thereof. 5 is the body of the connector provided with a horizontal cylindrical orifice 6 and a vertical cylindrical orifice 7 extending into the horizontal orifice. 8 is a reflector which is formed integral with the connector body 5.

35 9 is a cylindrical member formed of insulating material which fits within the horizontal orifice 6. The inner end of the member 9 or the end adjacent to the reflector is provided with an internally threaded orifice 9^x in which the screw threaded metal portion of the bulb 10 is screwed, such metal portion being provided with the usual centre end contact 10^x. The opposite end of the member 9 is provided with orifices 9° and 9', the inner end of the orifice 9° extending adjacent to the orifice 9^x and the orifice 9° extending partially into the orifice 9^x as clearly indicated in Fig. 2.

40 11 is a metal plug fitting within the orifice 9° and secured therein by means of a screw 11° extending through the upper portion of the body 5 through the member 9 against the plug 11. By

this means the member 9 and plug 11 are securely held in position within the orifice 6. The plug 11 is provided with a longitudinal orifice 11^x in which the terminal end of one member 12 of the ignition circuit extends to form a conductive connection thereto.

13 is a cylindrical plug extending into the orifice 9' and at its inner end into contact with the centre contact 10^x of the bulb 10. The plug 13 is provided at its inner end with an orifice 13^x into which the other terminal end 14 of the ignition circuit extends. Between the inner end of the orifice 13^x and the adjacent end of a plug 13 is formed a diametric orifice 13° which is located in central alignment with a vertical orifice 7 of the connector body.

15 is an insulating sleeve fitting the orifice 7 and extending at its lower end into contact with the annular shoulder 3^x of the battery terminal 3. 16 is a plug fitting within the sleeve 15 and provided at its upper end with a pin projection 16^x extending into and fitting the orifice 13° of the plug 13. By this means a conductive connection is formed between the plug 13 and the plug 16. The plug 16 is provided at its lower end with an orifice 16' into which the positive battery terminal 3 fits.

17 is an orifice formed in the connector body and in the member 9 so as to extend into the internally threaded orifice 9^x into which the bulb 10 is screwed. 18 is a contact screw which is threaded into the upper portion of the orifice 17 and is provided at its lower end with a reduced contact portion 17^x which may be adjusted so as to engage or disengage the metallic threaded shell of the flashlight bulb 10.

5^x is a lug formed in the rear portion of the body 5 to each side of which are screwed arms 18' which incline downwardly and are preferably formed of spring material and provided with hooked ends 18^x which extend around the rim 1^x so as to support the body 5 of the connector rigidly in place and form a means for grounding such body to the battery casing.

19 is a strip of conducting material provided with a hooked end 19^x at one end and an annular portion 19° at the opposite end through which the negative terminal of the battery extends so as to form a means for grounding such negative terminal to the battery casing.

When the device is set up as above described, a circuit extends from the positive terminal of the battery 3 through the plug 16, plug 13 to one member of the ignition circuit 14 and through the ignition returning back by the member 12 of

the circuit to the plug 11, the current thus passing through the plug to the screw 11° and to the connector body 5 and from thence through the supporting arms 18' to the battery case 1, thereby completing the circuit through such case to the grounding strip 19 leading to the negative terminal of the battery.

A circuit is also formed from the positive terminal 3 of the battery through the plug 16 and plug 13 to the centre contact 10^x of a bulb 10 and from thence through the contacts 17^x and screw 17 to the body 5 and from thence through the supporting arms 18' to the battery casing 1 and to the return grounding strip 19 leading to the negative terminal of the battery.

If it is desired to use the bulb 10 as a signal bulb, the terminals 12 and 14 of the ignition circuit may be left in their connected position within the orifices 11^x and 13^x and the screw 18 is screwed down into contact with the bulb 10, the current then passing through the bulb.

If it is desired to use the bulb 10 as a portable flashlight, the terminals 14 and 12 of the ignition circuit are disconnected and the battery carried from place to place by means of the handle 2, the circuit through the flashlight bulb being unaffected by the withdrawal of the ignition circuit terminals.

It may be noted that a connector such as I have described may be easily assembled or disassembled without the use of any tools.

What I claim as my invention is:—

1. A combination ignition circuit and flashlight battery comprising a connector body, means for mounting the body on a battery case so as to be grounded thereto, an insulating member carried by the body, ignition circuit terminals carried by the member, one of which is grounded to the body, means insulated from the body for forming a connection between the other ignition circuit terminal and an ungrounded battery terminal, means for mounting an incandescent bulb in the insulating body so that its end contact engages the ungrounded ignition circuit terminal and a peripheral bulb contact carried by the body.

2. A combination ignition circuit and flashlight battery comprising a connector body, means for mounting the body on a battery case so as to be grounded thereto, an insulating member carried by the body, ignition circuit terminals carried by the member, one of which is grounded to the body, means insulated from the body for forming a connection between the other ignition circuit terminal and an ungrounded battery terminal, means for mounting an incandescent bulb in the insulating body so that its end contact engages the ungrounded ignition circuit terminal and a peripheral bulb contact carried by the body, and adjustable in and out of engagement with the metallic portion of an inserted bulb.

3. The combination with a battery case and

terminals, one of which is grounded to the case, of a flashlight body mounted on the ungrounded battery terminal and grounded to the battery case, ignition circuit terminals carried by the body, and means for forming two independent circuit connections, one extending from one ignition circuit terminal through the body to the battery terminal and the other from the flashlight terminal through the body to the battery terminal, and means for grounding the other ignition circuit terminal to the flashlight body, and means for opening and closing the circuit between the flashlight and the flashlight body.

4. The combination with a battery case and terminals one of which is grounded to the case, of a flashlight body mounted on the ungrounded battery terminal, ignition circuit terminals carried by the body and means for forming two independent circuit connections, one extending from one ignition circuit terminal through the body to the battery terminal and the other from the flashlight terminal through the body to the battery terminal, and means for grounding the other ignition circuit terminal, and means for grounding the flashlight terminal to the body.

5. The combination with the battery casing and terminals, and means for grounding one of said terminals to the casing, of a connector body carrying a reflector at one end and having a horizontal orifice extending therethrough from the reflector, a portion depending from the body having a vertical orifice extending therethrough into the horizontal orifice of the body, an insulating plug fitting the horizontal orifice and having a bulb receiving socket at one end and plug receiving orifices at the opposite end, a metallic plug secured in one orifice and grounded to the connector body and adapted to receive one terminal of an ignition circuit, a plug fitting the other orifice and adapted to receive the other terminal of the ignition circuit and to contact the centre contact of an inserted bulb, a metal plug extending through the vertical orifice and insulated from the walls thereof and contacting the horizontal plug, and means for connecting the lower end of the body to the ungrounded terminal of the battery.

6. The combination with a battery case and terminals one of which is grounded to the case, of a flashlight body mounted on the ungrounded battery terminal and grounded to the battery case, ignition circuit terminals carried by the body, and means for forming two independent circuit connections, one extending from one ignition circuit terminal through the body to the battery terminal and the other from the flashlight terminal through the body to the battery terminal, and means for grounding the other ignition circuit terminal to the flashlight body.

DOUGLAS ROLPH CLARKE.
